(57) CLAIM

The ornamental design for a handbag as shown and described.

DESCRIPTION

FIG. 1 is a front, right view of the handbag showing my new design;
FIG. 2 is a front view thereof;
FIG. 3 is a back view thereof;
FIG. 4 is a left side view thereof;
FIG. 5 is a right side view thereof;
FIG. 6 is a top view thereof; and,
FIG. 7 is a bottom view thereof.

The broken lines in the figures depict portions of the bag that form no part of the claimed design.

1 Claim, 7 Drawing Sheets
